UNITED STATES PATENT OFFICE

2,329,306

COIN CONTROLLED MAILING MACHINE

Linden A. Thatcher, Stamford, Conn., assignor
to Pitney-Bowes Postage Meter Co., Stamford,
Conn., a corporation of Delaware.

Application May 16, 1941, Serial No. 393,714

9 Claims. (Cl. 194—83)

This invention relates to a coin controlled calculating unit which is particularly adapted for use with a coin-operated mailing machine and is a continuation in part of Patent No. 2,290,920 which discloses a complete coin controlled mailing machine.

In the machine of said co-pending application a credit is set up in accordance with the accumulative unit value of one or several coins of one or more denominations, and the printing of stamps is effected in accordance with a desired value which is manually selected. As each postage impression is printed on letters when inserted in the machine, the value of the stamp is subtracted from the total credit or balance, and after the credit is exhausted the machine will become non-operative.

The present machine also provides for these features but in an improved order through an improved calculating mechanism which will add and subtract in both units and tens orders, and will provide for both adding and subtracting operations simultaneously. By means of this improved arrangement the machine is also adapted to receive coins at the same time letters are inserted for printing, if desired.

It is the principal object of this invention therefore, to provide an improved calculating unit for a coin-operated mailing machine, wherein the values of the coins may be accumulated in both units and tens orders and wherein values printed may be subtracted in a units and tens order.

It is a further object to provide for the subtraction of fractional unit values from the credit values.

It is a further object to provide, in connection with the selection of values, means whereby devices are arranged by the selecting member in an order for the subtraction of both units and tens values.

It is another object to provide a units and a tens selector dial, and transfer means whereby the tens dial is moved when the units dial is moved from "9" to "0."

It is another object to provide a compensating unit to return the selector to its "0" position, if during a printing operation, a credit value is reduced to less than the value at which the selector had been set.

It is another object to provide means whereby the compensating unit may be controlled in both a units and tens order.

With the above and other objects in view, which will appear as the description proceeds, the invention resides in the combination and

arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a front elevational view showing the mechanism of the machine in general;

Fig. 37 is the final operation view after the printing of the 4¢ value and return of the mechanism to its zero position.

General description

In Figs. 1 and 2 the general structure of the machine is shown, in which are included: a power drive 1, a meter unit 2 having rotary printer 3 combined therewith, coin receiving slots 4, coin detectors and coin controlled actuators 5 and 5a, a calculating unit 6, and value selection means 7.

By means of the above named members, coins, after being inserted in the appropriate coin slots 4, are adapted to control the mechanism of the calculating unit 6 to set up a credit which will agree with the accumulated value of the coins inserted, the power drive having been energized by means of the first coin inserted. After a credit has been established, any part of that credit may be selected as a value to be printed, by rotating a manual selection knob 21 to the value desired. The selection operation will effect the setting of value type wheels in the printing drum 3 and mechanism in the calculator 6, to condition the machine for the printing of a postage stamp impression upon a letter inserted between the rotary printer 3 and an impression roller 8. The insertion of a letter will effect the trip of a drive clutch to connect the drive with the rotary printer and meter unit, also will actuate the calculating mechanism when subtracting a selected value from the credit, i. e. the value of the stamp which is printed on the letter.

In the aforementioned co-pending application

the entire mechanism referred to above is specifically described, but in this application such parts which are the same or similar to those in said co-pending application, will not be described, except as required for clarification.

In the device of this invention, attention will be drawn to the calculating unit and its control in accordance with values set up by the coins or by values selected for printing. The features which will be emphasized will include the setting of a credit in either a units or a tens differential system, the selection in either a units or tens order, the selection of a fractional value, such as a one and one-half cent postage value, and the return of the selector mechanism to a zero position at any time when the credit is reduced to less than the value set in the selector. In the latter operation, a compensating unit is provided which also operates in a units and tens order. By use of the units and tens order of control, transfers are provided where necessary.

To understand generally where the mechanism is found which controls each of the above named features of operation, a brief description of the controlling mechanism will now be made.

A coin upon being inserted in its appropriate slot 4, will pass through coin chute 12, into coin detector 5 and a coin actuator unit 5a, Fig. 10. Here each coin is controlled in such manner that the outer diameter provides a selecting medium whereby a connecting link 13 is moved a predetermined distance, as determined by the said diameter of the coin, which movement is transferred through mechanism, generally indicated at 14, to pinion shifting elements, to control the shifting of pinions 15, generally indicated in Figs. 6, 10 and 11. Associated with said pinions 15, are mutilated gears indicated at 16, Fig. 3, three of which are indicated at 16u, and are arranged for units value control, and two of which are indicated at 16t, and are arranged for tens value control.

The desired pinion 15, is thus moved under control of the coin, into operative relation with an associated mutilated gear 16, which gears are continuously driven, and the pinion is driven thereby a distance equal to the number of teeth on the mutilated gear. When a units pinion is rotated, the distance of rotation is transmitted to differential mechanism indicated at A, Figs. 3 and 4. When a tens pinion 15 is rotated, the movement is transmitted to a differential indicated at B. Referring to Fig. 3, a partition indicated at 20, divides the units from the tens control mechanisms, the units control being indicated at the left and the tens control at the right of said partition 20.

Each of the differential devices mentioned, as well as others which will be referred to later, comprise planetary gear mechanisms, wherein entries are made in either the sun or the ring gear and wherein the result is taken from the planet gear movement, commonly called the spider. In the above described operation, where the rotation of a pinion 15 is transmitted to the tens differential B, entry is made in the sun gear of the differential B, and the result is transferred through a gear connection from the spider to a cross-over shaft 17, Fig. 4, which has fixed thereto a gear which meshes with the sun gear of another differential indicated at C. Each of the differential elements will be described in detail later.

The rotation of the spider on the units differential A is transmitted to a units numeral wheel

18u, and the rotation of the spider from the tens differential C is transmitted to a tens numeral wheel 18t. Hence, the accumulation of credit is retained in each of the differentials A and B, and the values are indicated upon the units and tens wheels 18u and 18t.

Registration of the coin controlled credit values is also made in the compensator unit, generally indicated at 32, Figs. 4 and 35.

After a credit has been set up, the next operation comprises the manual selection of a value which it is desired to have printed as postage on a letter. The selector knob 21, Figs. 1 and 2, is rotated to rotate a shaft 22, Fig. 11, and gear 23 thereon. Through a units and tens control cam mechanism 24, Figs. 7 and 11, which is rotated with the shaft 22, a units mutilated gear structure 25u and a tens mutilated gear structure 25t, Fig. 3, are adapted to be adjusted with relation to units and tens pinions 26u and 26t respectively. Also, when a selection is made, the gear 23 will drive a gear 27 on shaft 28, Fig. 4, to actuate the sun gear of a differential indicated at E, wherein the units values are set during a selection operation. When a value beyond 10 is selected, a transfer is provided by means of transfer mechanism 31, Fig. 4, which controls the drive of the sun gear of a differential D to thus set the tens value therein.

After setting a selected value and tripping the machine by inserting a letter between the printing drum and impression roller, in a manner described in the aforesaid copending application, the units or tens mutilated gears 25u and 25t will be rotated to drive the pinions 26u or 26t and effect a subtracting operation. When subtraction is effected, the drive of the pinion 26u is transmitted through the ring gear of the differential A, then from the spider of said differential A to the units indicator wheel 18u, also to the ring gear of the units differential E. From the spider of the differential E, the compensator 32 is also adjusted in accordance with the selected value during a printing operation. The subtraction of the tens selection through pinion 26t is transmitted to the ring gear of the differential C, and from the spider of said differential C, the drive is transmitted to the tens numeral wheel 18t and the ring gear of the differential D. Also from the spider of the differential D the compensator 32 is adjusted.

If at any time the credit remaining is reduced to a value during any printing operation to an amount which is less than the value set up in the manual selector 7, provision is made to have the selector return to a zero position. As a result of this operation it will become necessary for the operator to reset the selector before another printing operation can be effected. If there is an insufficient amount of credit remaining for the postage which it is desired to print next, further coins must be inserted to increase the credit to the necessary value.

The compensating mechanism 32, previously referred to, is provided for the purpose of preventing the printing of a value greater than the credit value, also for controlling or initiating the operation for the return of the selector dial to zero at the end of an operating cycle. When said compensator is actuated through the credit mechanism, it is driven in a positive or clockwise direction, as viewed from Fig. 35, to receive the credit value set up in the credit differential mechanisms A, B, and C. When selection and subtracting operations occur, the compensator is

5 moved in a negative or counterclockwise direction by differentials D and E and transfer 31, Fig. 4. Upon reaching a predetermined point in a negative direction during a subtracting operation, a zero return clutch, Fig. 32, is tripped to drive the selector dial to a zero position.

The mechanism relating to the above features will now be described in detail.

Four coin slots, indicated at 4, Fig. 1, are provided for the reception of quarters, dimes, nickels and pennies, as indicated by Q, D, N and P respectively and are connected through coin chutes 12 with coin detector units 5, which units may be of any commercial type suitable for rejecting spurious coins. After passing through the coin detectors, the said coins will enter the coin actuator units 5a, shown in Fig. 10.

Said actuator units comprise side guide plates 34 which are supported by horizontal bars 35, forming a part of the general machine frame structure F. A coin channel member 36 guides the coins to a coin stripper disc 37, which disc is driven by a continuously rotating shaft 38, driven by the motor drive 1. Each disc 37 is notched to provide a seat 41 and a coin engaging shoulder 42.

A coin stop 43, fixed to a shaft 49, has one nose-shaped end thereon normally urged into the path of coins 40, by means of a spring 45. The coin stops 43 are adapted to be removed from the path of each coin once during each revolution of the coin discs 37.

After the coin moves to the receiving position of Fig. 10, within the notched portion of the disc 37, it is moved with the disc 37, by the engagement of the shoulder 42 therewith. During such movement, the edge of the coin will engage a rocker lever 46 to rock said lever about its supporting shaft 47. By means of the link 43, previously mentioned, said rocker lever 46 is connected with a lever 48, which lever is fixed to a shaft 50 carrying another lever 49. The lever 49 has a forked end 49a, which engages a pin 51, projecting from a slide-rod 52. See also Figs. 6 and 11. In Fig. 6, four sets of levers 48-49 are indicated, and each has the name of a coin indicated thereabove to designate the particular coin with which each is associated. Each slide rod 52 is also indicated with an exponent letter, 52Q, 52D, 52N and 52C, which agrees with the corresponding coin denomination with which said rods are associated.

Secured to one of each of the rods 52D, 52N and 52C are pinion shifting members 53, which depend downwardly, and each has a forked end 59 engaged with grooved portions 54 of associated pinions 55u or 55t. Secured to the rod 52Q are two pinion shifting members 53a-53b which are engaged with associated pinions 55a and 55t. Said pinions 55u and 55t are mounted on splined portions 56u and 56t of shafts 57u and 57t, Fig. 3. Said shafts 57u and 57t are adapted to freely rotate within a common bearing 58 and end bearings 60-60, and further have gears 61u and 61t fixed thereon respectively. It will thus be noted that in the case of the dime, nickel and cent there is only a single pinion shifting member but in the case of the quarter there are two shifting members, one to adjust the tens pinion 55t and the other to adjust the units pinion 55u.

Cooperating with the pinions 55u and 55t are the mutilated gears generally indicated at 16. As best shown in Figs. 3 and as previously stated, said mutilated gears are divided into two sets, one set of three designated at 16u, and compris-

ing a one-toothed gear and two five-toothed gears, and another set of two designated as 16t, and comprising a one-tooth gear and a two-toothed gear. For clarity the number of teeth is indicated below each gear, and further, the first initial of the particular coin denomination which the gear represents is indicated on the gear. Said gears are fixed to a shaft 62, which shaft is continuously driven from the motor drive 1.

When a coin is moved by the coin disc 37, Fig. 10, into engagement with the rocker lever 46, the said lever is rocked a predetermined distance under control of the diameter of the coin, and through the link 13 and levers 48-49, will move the slide-rods 52 and attached shifting members 53, to move an associated pinion 55u or 55t into the path of a mutilated gear 16u or 16t. The coin discs 37 are arranged so that a coin of each denomination could be moved simultaneously past the levers 46 by the shoulders 42 of the respective coin discs 37 because the mutilated gears of each group have their teeth arranged in a staggered order. By means of a base 39, which is adapted to be rocked about the shaft 47 once during each rotation of the coin discs 37, the rocker levers 46 and pinions 55u and 55t are returned after credit setting is effected.

Allocation of units and tens coin values

It will now be shown how the values of the several coins are divided into either units or tens values. All tens values, including all multiples of ten, are set up in the tens controlling mechanism indicated to the right of the partition 20, Fig. 3. All units values from 1 through 9, either as a single unit or in combination with a tens value, are set up in the units controlling mechanism indicated to the left of the partition 20, Fig. 3.

In the process of credit setting, by means of the four coins which are adapted to be used in this machine, the units values are taken from the cent and nickel, also the five units in the quarter. The tens values are taken from the dime and the twenty value in the quarter. To provide for this condition in credit setting, three units mutilated gears are included, a one-toothed gear for the cent, a five-toothed gear for the nickel, and a five-toothed gear for the five units value in the quarter. On the tens side two mutilated gears are provided, one of which has a single tooth thereon, and which agrees with the dime. The other mutilated gear has two teeth thereon, which agrees with the two tens value of the quarter coin. When a quarter is inserted in the machine therefore, the amount added in the credit is split into two parts, two tens of the tens value thereof being registered on the tens side, and the five units value thereof being registered in the units side. In each of the other coins, the cent, nickel and dime, the total value of each is entered direct. When a quarter passes through the coin devices therefore, two pinions 55u and 55t are adjusted into operative relation with the 5 toothed units gear 16u, and the 2 toothed tens gears 16t, respectively.

Differentials (A, B, C, D, E)

When the several mutilated gears 16 function to drive the pinions 15 on either the units or the tens side, the values are transmitted to either of two differentials indicated at A for the units, and B for the tens values.

Each of the said differentials A and B as well

as the aforementioned differentials C, D, and E are of the planetary gear type which include three principal parts namely; a sun gear, a ring gear, and planet gears, the planet gears being mounted upon a support normally referred to as the spider. To simplify the description of these planetary gear differentials, the three principal parts will be designated by a letter R for the ring gear, S for the sun gear, and P for the planet or spider, followed by the letter designating the differential itself.

Units credit

Referring to the differential A, Figs. 3 and 4, which is actuated by one of the units mutilated gears 16u when a units value of one or five is set up, the sun gear SA is carried by a sleeve 63, which sleeve is freely rotatable upon a shaft 64. The shaft 64 is mounted in a fixed position within the frame structure and the differential revolves about the shaft. Fixed to the sleeve 63 is a gear 65 which is adapted to be driven in accordance with the units value of the coin either one or five steps by the gear 61u on the units value drive shaft 57u, the drive of said gear 61u being determined by the mutilated gears 16u through pinions 55u. The rotation of said sleeve 63 and the sun gear SA, will effect rotation of the spider PA, and a gear 70 which is fixed to the spider PA. Meshing with the gear 70 is a pinion 66 fixed on a shaft 67 which shaft also has a gear 68, fixed thereto. Said shaft 67 is freely rotatable in bearings 69a-69b. Meshing with the gear 68 is another gear 71, which is combined with the units numeral wheel 18u and a sleeve 73, said sleeve being freely mounted upon a shaft 74. The shaft 74 supports each of the aforementioned numeral wheels 18u, 18t and a hundreds numeral wheel 18h.

The gear 70 of the differential A, further meshes with a pinion 75, which pinion is fixed to a shaft 76 supported in bearings 77-77. By means of a gear 78, fixed on the shaft 76, a drive from the gear 70 is transmitted to a gear 79 fixed to the ring gear RE of the differential E. From the said gear 79, the drive is continued through the planet gears or spider PE to a gear 81 which is fixed to said spider. Said gear 81 meshes with a pinion 82 associated with the compensating unit 32 and is adapted to control the units value setting of said compensating unit. Further reference will be made to said compensating unit and pinion 82 later.

As thus far described, it has been shown how a units credit value may be set up in the differential A and differential E from which the units numeral wheel 18u and the units side of the compensator are adjusted in accordance with the units credit value.

60

Tens credit

It will now be shown how a tens credit value is set up.

If a dime or a quarter is inserted in the coin slots 4, either of the two mutilated gears 16t indicated by D and Q on the tens side, will have one of the pinions 55t moved into engagement therewith, which pinions will be rotated in accordance with the number of teeth on the mutilated gears.

Gear 61t, which rotates with the shaft 57t and pinions 55t, meshes with a gear 83, Fig. 3. Said gear 83 is fixed to a sleeve 84, Fig. 4, which sleeve also has fixed thereto the sun gear SB of the differential B. The sleeve 84 is supported by the

75

shaft 64, which shaft also supports the differential A and is rotatable about said shaft. A gear 85, which is fixed to the spider PB of the differential B, meshes with a pinion 86, fixed to the crossover shaft 17. Also fixed to the shaft 17, and rotatable with the pinion 86, is a gear 87 which meshes with a gear 88. Said gear 88 is carried by a sleeve 89, which sleeve also carries the sun gear SC of the differential C. A gear 91, which is fixed to the spider PC of said differential C, meshes with a pinion 92 fixed on a shaft 93. Said shaft 93 is supported in bearings 69b and 69c and is positioned in axial alignment with the shaft 67. Also fixed to said shaft 93 is a gear 94, which gear meshes with a gear 95 fixed to the tens numeral wheel 18t to provide the drive for said numeral wheel.

Through the last named mechanism therefore, the tens value, when controlled by either the dime or quarter, will be transmitted first through the differential B, then through the differential C to the tens numeral wheel 18t.

The tens credit value is also set up on the tens side of the compensator unit, which is accomplished by driving a compound gear 90—96 by the gear 91 of the differential C. Said compound gear structure is supported upon a sleeve 97 which is freely rotatable about the crossover shaft 17. The gear 90 meshes with the gear 91 and the gear 96 meshes with a gear 98, which is secured to and forms a part of the ring gear RD of the differential D. Another gear 101, which is fixed to the spider PD of the differential D, meshes with a pinion 102, which is fixed to a shaft 103. Rotation of the shaft 103 will effect rotation of the tens element of the compensator unit 82, the details of which are to be later described. Said shaft 103 is suitably supported in bearings 104—104.

Transfer

A transfer mechanism is provided between the differential A and differential B, Fig. 4, whereby a units value which is either added or subtracted, and which increases or decreases a previous value above or below ten, will effect a transfer through the differentials B, C and D to the tens compensator.

Said transfer mechanism comprises a Geneva gear 105 and locking element 105a, each being fixed to the shaft 76. The gear 105 is fixed to a sleeve 106 on which gear 78 is also fixed. Therefore, the gear 78 is rotated with the pinion 75, associated with the differential A, when said pinion is rotated by the gear 70 of the spider PA. The Geneva gear 105 meshes with a Geneva pinion 107 to drive a transfer shaft 108 to which it is fixed. Also fixed to the shaft 108 is a pinion 109 which meshes with a gear 109, said gear being joined with a gear 99 by means of a connecting sleeve 99a which is freely rotatable about the crossover shaft 17. The gear 99 meshes with a gear 120, which is fixed to the ring gear RB of the differential B.

The differential B is connected with the differential C through gear 85, pinion 86, shaft 17, gears 87 and 88, the latter gear being associated with the sun gear SC of the differential C. From the spider PC of differential C, the differential D is driven, and from the spider PD of differential D, the tens compensator shaft 103 is driven. Hence, a transfer effected by the Geneva transfer 105, 107, will be transmitted to the tens compensator.

Selection

After the desired credit has been set up, the operator will next select the value which is to be printed as postage on the letter.

Referring to Fig. 3, a compound mutilated gear structure is indicated at 110, each of which gears have a different number of teeth in the order indicated by the numerals directly below the gears in Fig. 3. It will be noted from said numeral indications that there are twice as many teeth on each of the gears as their particular value would indicate. For example, the two-toothed gear instead of providing for a value of two provides for a value of one, the three-toothed gear provides for the value of one and one-half, the four-toothed gear provides for the value of two and so on through 18 which provides for the value of 9. This arrangement is provided particularly for the purpose of including a one and one-half cent value. It will also be noted that the 2, 3 and 4 toothed gears are in consecutive order but that this order changes to alternate gears after passing the four-toothed gear. The purpose of this is to provide an easier cam motion which will require movement of the mutilated gear unit in even steps, first in one direction for the 2, 3, 4, 6, 8 and 10 tooth values then in a reverse direction for the 12, 14, 16 and 18 toothed values. The greatest jump will be between the 16 and 18 toothed value. With said mutilated gear 110, selection is limited to the units values.

A second mutilated gear 111 is also provided for the selection of tens values. In the gear 111 there are three different sets of teeth and include a 2, 4 and 6 tooth gear which provide for the values of 10, 20 and 30. Each of said mutilated gear elements 110 and 111 is also mounted upon a splined shaft 112, which shaft is mounted in suitable bearings 113—113 and is adapted to be driven during a printing cycle of operation by a drive 116 from the motor drive 1.

Adjustment of the units mutilated gears 110 is provided by means of a cam 114, Figs. 6, 7, 9 and 11 which is fixed to a sleeve 115. Said sleeve 115 is fixed to the selector shaft 22, which shaft is mounted in suitable bearings 38—39 and extends forwardly from the front of the machine, and further has the manually operable knob 21 thereon, whereby said shaft is rotated. Also mounted on said shaft is the gear 23 previously referred to, and a pair of dial indicator members 117—118. The inner indicator member 117, Figs. 1, 6, 9 and 11, comprises a disc having the units numerals thereon and the outer member 118 comprises a ring having the tens numerals thereon. Upon rotating the knob 116, the units indicator dial 117 will be rotated to effect a unit setting at each tenth of a revolution and after passing from the 9 to the 10 position, the tens dial will be moved with the units dial one place. The tens dial 118 will then remain in a fixed position until the units dial completes another revolution, when the tens dial will move to the number 2 position.

Joined with the units cam 114, on the sleeve 115, is a half-cent cam 119, each of which cams are rotated with the selector shaft 22. A tens cam 122 and a gear 123 are fixed to a sleeve 121 and are freely rotatable about the shaft 22. A geneva gear 124, Figs. 8, 9 and 11, is fixed to the shaft 22, and a gear 125 is fixed to the units dial 117. A shaft 126, supported in a U-shaped bearing structure 127, carries three pinions 128a, 128b and 128c, which normally engage the gear 123, geneva 124 and gear 125 respectively. By

means of said gear arrangement, a tens transfer is effected through the geneva 124-124a, which in turn will effect movement of the tens indicator 118 through the gears 125, 125a during the transfer period, and will further effect movement of the tens cam 122 through the gears 123 and 123a.

Associated with the units cam 114 and tens cam 122, are slide rods 127 and 128 respectively, which are similar to the aforementioned slide rods 52, associated with the shifting of the pinions 55u and 55t. A rocker lever 133 is pivotally mounted at 134, Fig. 7, and has a cam roller 135 engaging a cam slot 139 in the units cam 114, and further has a slotted end 136 engaging a pin 131 projecting from the rod 127. Another rocker lever 137 is also pivoted at 134, and has a cam roller 138 at one end, which engages a cam slot 140 in the tens cam 122, and further has a slotted end 141 which engages with a pin 132 projecting from the rod 128.

A gear shift yoke member 142, Figs. 3, 7 and 11, is fixed to the slide rod 127 and has its yoked end engaged with a grooved sleeve 143, which sleeve forms a part of the complete mutilated gear structure 110 for the units value. Another gear shift yoke 144, Fig. 3, is fixed to the slide rod 128 and has its yoked end in engagement with the grooved sleeve 145, which sleeve forms a part of the tens mutilated gear structure 111.

Also associated with the cam 114 is a units type adjusting means for setting the type value in the printing drum 3, which comprises a rocker lever 146 pivotally mounted at 134, and having roller 147 engaging a cam slot 148. A link 151 joins the rocker lever 146 with an arm 151a, Fig. 1, which arm is connected with the units type wheel of the type wheel structure 159, Fig. 5, in a manner completely described in the aforesaid co-pending application. In a like manner a tens arm 165 and a half-cent arm 166 are linked with rocker members 167, 168, which are associated with the tens and half-cent cams 122 and 119 respectively.

In selecting the value for printing, as thus far described, it will be noted that the units dial 117 will first be rotated to set a selected value, and when it rotates to the tens position, a transfer is effected to move the tens dial 118 to the next higher order. Also, the units mutilated gears 110 and tens mutilated gears 111 will be adjusted to positions agreeing with the value set up. Also, the type setting levers 151a, 165, 166 in the meter unit 2, will be adjusted to effect the proper setting of value type wheels 159, Fig. 5, in accordance with the selected value.

Selection entered in differentials

In addition to setting a selected value in the dials 117-118, in the mutilated gears 110 and 111, and in the type wheels of the meter unit 2, the said value selected is entered into the differential system, and compensating system.

When the selector shaft 22 is rotated by manipulation of the knob 21, the gears 23 and 27 are rotated to thus rotate the shaft 28, Fig. 4. Fixed to said shaft 28 is a sleeve 152 which carries the sun gear SE of the differential E. In this differential, the selected units values are set-up by means of the gear 81, which is connected with the spider PE. Said gear 81 also meshes with pinion 82, which is adapted to adjust the units element of the compensator 32 in accordance with the selection made.

Selection (tens transfer)

When the selection is for a value greater than 9, a Geneva gear 163, which will have rotated through a full revolution when the shaft 28 and sun gear SE rotate through a full revolution, will upon passing through the tens position, rotate a Geneva pinion 154 of the transfer 31. This will effect rotation of the shaft 103 and the setting of the transferred value on the tens side of the compensator. Through a gear 149, which is joined with the pinion 154, and a gear 150 which is joined with the sun gear SD, the selected tens value is entered into the differential D.

Letter Printing Cycle

After the desired value which is to be printed is selected, the mechanism is in condition for the printing operation and for the subtraction of the printed value from the differential system and compensating mechanism. The machine cycle of operation is effected when a letter is inserted in the machine to trip same in a manner which is fully described in the said co-pending application.

After a letter tripping operation, the splined shaft 112, Fig. 3, is driven through one revolution and the units mutilated gears 110 and tens mutilated gears 111 are rotated therewith. Whichever mutilated gear is adjusted to driving relation with the units pinion 26u or tens pinion 26t, a drive of the pinion will be effected in accordance with the number of teeth which engage therewith. When the units pinion 26u is rotated, a shaft 155 and a pinion 156 are rotated therewith. The pinion 156 meshes with a gear 157 which is fixed to the ring gear RA of the differential A. The rotation of the ring gear RA will effect rotation of the spider PA and the gear 70 fixed thereto.

Rotation of the gear 70 will effect rotation of the pinion 66, shaft 67, and gear 68, Fig. 4, to thereby rotate the gear 71 and the units numeral wheel 18u. In this manner the units numeral wheel is adjusted to subtract the selected value therefrom.

A pinion 75 is also driven by the gear 70 of the differential A and will effect the drive of the shaft 76 and gear 78 thereon. The gear 79 which, as previously stated, is fixed to the ring gear RE of the differential E, meshes with the gear 78 and effects the subtraction of the selected value from said differential E. The gear 81 of said differential E, associated with the spider PE, meshes with the pinion 82 of the units compensator element, to therefore effect the subtraction of the selected units value from the compensator.

If a tens value is selected, the selected gear of the tens mutilated gear unit 111, Fig. 3, will engage and rotate the tens pinion 26t, thus rotating a shaft 161, and a pinion 162 thereon. The pinion 162 meshes with a gear 163, which gear is fixed to the ring gear RC of the differential C. Rotation of the ring gear 163 will effect rotation of the spider PC and the gear 91, Fig. 4, secured thereto. From said gear 91, the pinion 92, shaft 93 and gear 94 are driven. The gear 94 meshes with the gear 95 of the tens numeral wheel 18t and said tens numeral wheel is adjusted in accordance with the tens value selected. Also meshing with the gear 91 is the pinion 90, which pinion is combined with the gear 96, the latter meshing with the gear 98, fixed to the ring gear 70 RD of the differential D. The gear 101, asso-

ciated with the spider PD of the differential D, meshes with the pinion 102 to effect the drive of shaft 103, which controls the movement of the tens element of the compensator 32.

It has now been shown how a total credit value is registered in the numeral wheels 184, and 185, also how the value selected for printing is subtracted from said numeral wheels. It has further been shown how the credit setting effects the setting of the compensator mechanism 32, and how each value as selected, adjusts the compensator, and finally how the compensator is again adjusted during the subtraction of the selected value when printing.

Compensator

It will now be shown what the purpose of the compensator is, and how it is constructed.

The purpose of the compensator is to provide a control for the return of the selector shaft 22 and parts associated therewith to a zero position after the credit balance becomes less than the value last selected during any machine cycle of operation. This makes it necessary for an operator to reset the selector before starting another operation, and if it is desired to set a value greater than the remaining credit, further coins must be inserted in the machine.

By means of a mechanically operated electric switch 170, Fig. 35, electrical contacts 174-175 are closed, and upon approaching the end of a cycle of operation, a circuit will be completed to energize a solenoid 171. Any suitable control or cut-in means may be used, and for the purpose of simplification, such means is diagrammatically shown in the electrical circuit at 188. This will effect the release of a selector return clutch mechanism, Fig. 32, to return the selector shaft 22 to its zero position.

Referring to Fig. 35, a switch arm 172 of insulating material is carried by a shaft 173, which arm has an electrical contact 174 thereon, normally spaced apart from a contact diagrammatically indicated at 175. An arm 176, fixed to the shaft 173, has a roller 177 mounted at the free end thereof, which roller engages cam surfaces 178, 181 of rocker members 182 and 183 respectively. The member 182 is associated with the units compensator control, and the member 183 is associated with the tens compensator control. When either of said members 182 or 183 is rocked about a supporting shaft 184 in a clockwise direction, as viewed from Fig. 35, the roller 177 will be engaged by a rise 185 or 186 on the cam surfaces 178, 181 respectively. Said engagement will effect the rocking of the arm 176 and shaft 173 to thereby rock the switch arm 172 and close the switch contacts 174-175 of the switch 170. Energization of the solenoid 171 will result at the end of the operating cycle, to effect the release of the zero return clutch in a manner to be later described.

Rockers members 182 and 183 are formed to the contour of an inverted 'Y', and adjacent thereto in a spaced apart relation are similarly shaped members 187-188 to provide pairs of supporting members between the downwardly disposed arms of which are units compensator pawls 191 and 192 suitably supported upon pins 193 and 194, and tens compensator pawls 195 and 196 suitably supported upon pins 197 and 198 respectively. The upper surfaces of the members 187 and 188 have three notches therein respectively as noted at 201 and 202. Detent levers 203 and 204 are associated with the members 187, 188 respectively

and have their detent ends in engagement with the notched portions thereof. Each of said detent pawls 203 and 204 is urged to a detent position by springs 205 and 206 respectively. The pawls 191 and 192 have their pawl ends urged in a downwardly direction by springs 199-199 while the pawls 195 and 196 have their pawl ends urged downwardly by springs 200-200.

A disc 211 has a protruding tooth 212 and is fixed to the hub portion of pinion 82, which pinion is freely mounted to rotate about the shaft 103. A disc member 213 having a protruding tooth 215, Fig. 36, is fixed to shaft 103. A cam disc 216 having a cam surface 218, and a cam disc 217 having a cam surface 219, are fixed to the sleeve 214 which supports the tens toothed disc 213. The pawl 191 is adapted to ride upon the peripheral edge of either the toothed disc 211 or the cam disc 216. During the units credit setting i.e. from 0 through 9 only the disc 211 is rotated, hence the pawl 191 will ride along the edge of disc 211. When a tens credit value is entered however, the disc 216 will rotate clockwise and the cam 218 will move the pawl 191 from engagement with the disc 211 to engagement with the peripheral edge of the disc 216, which is out of the path of tooth 212. The pawl 191 has a slotted portion 221 to provide clearance for the cam disc 217 to pass freely therethrough and the pawl 192 has a slot 222 to provide clearance for the disc 218. The disc 214 and the disc 217 are adapted to cooperate with said pawls 191-192. Pawls 195 and 196 are adapted to cooperate only with the toothed disc 213.

The pawl supporting members 182-187 and 183-188 are normally arranged in the position shown in Figs. 11 and 35, when the machine is in its home position i.e. with no credit therein. In said position, the pawls 191 and 195 engage the peripheral edges of the discs 211 and 213 respectively, while the pawls 192 and 196 are positioned directly above the toothed portions 212 and 215. When a credit is entered into the compensator, the disc 211 will rotate in a clockwise direction, as viewed from Figs. 11 and 35, and upon completing a revolution, a transfer effected through the Geneva gear 153 and pinion 154, Fig. 4, will move the discs 213, 216 and 217 one step in a clockwise direction to set the credit value of ten therein. The first change in position of the compensator which takes place during credit setting therefore, is after the tens discs 213, 216 and 217 are rotated. During said latter rotation, the pawl 191 is cammed to a position above the path of the tooth 212 by the cam surface 218.

During a selecting operation, also during a subtracting operation, the units disc 211 is rotated in a counter-clockwise or negative direction the number of unit spaces agreeing with the value selected. First, rotation of said disc 211 will be effected through the number of unit spaces agreeing with the value selected, then the said disc is again rotated through the same number of spaces when the value is subtracted during a printing cycle of operation. Hence, if a selection of the total credit is made, the tooth 212 of the units disc 211 will return in a counter-clockwise direction to the "0" position during selection, then during the subtraction operation said tooth 212 will again move in the same direction, the same distance as that resulting from the selection. During the latter or subtraction movement, the tooth 212 will engage the end of pawl 191 to effect the rocking of the rocker members 182-187 about the shaft 184 to a negative

position, as indicated in Fig. 30. The rocking of the members 182—187 will in turn effect movement of the cam rise 185 across the roller 177, which will rock the arm 176, shaft 173 and switch arm 172 to close the switch 170. As previously stated, the closing of said switch will effect the return of the selector mechanism to a "0" position at the completion of a cycle of operation.

When zeroizing occurs, the discs 211 and 213 will be rotated in a clockwise direction, as viewed from Fig. 35, to move the toothed portions thereof, 212 and 215 respectively, to their zero positions or the position shown in Fig. 11. Upon arriving at said zero positions, the toothed portions 212—215 will engage the ends of pawls 192 and 196, which are now in the path thereof, and thereby rock the rocker members 187—188, and the cam members 178—181, to their normal positions, and further will effect the return of the arm 176 and switch arm 172 to their normal positions, and thus open the switch 170.

When selecting a value, there is a direct drive from the selector gears 23 and 27 to the differential E, and from the gear 81, which is associated with the spider PE, the pinion 82 is driven. Since the toothed disc 211 is fixed to the hub of the pinion 82, it will be rotated with the pinion 82 through ten unit positions for each full revolution thereof. Upon passing from the ninth to the tenth unit position, the shaft 103, on which the tens disc 213 and cam discs 216 and 217 are mounted, is rotated through one unit to establish a tens position. Said movement is effected by means of the Geneva gear 153 on shaft 28 which engages the Geneva pinion 154 on shaft 103.

Rotation of the cam disc 216 to a tens position will cause the cam surface 218 to rock the pawl 191 upward out of the normal path of the tooth 212 of the disc 211. With the pawl in said latter position, the tooth 212 is adapted to ride under the pawl when the disc 211 rotates in a counter-clockwise direction during either selection or subtracting operations. This can continue only so long as the tens cam disc 216 has moved to either a ten or greater than a ten position. In a later part of the description, a specific example will be taken to describe several steps in the credit setting, of a value and the selection and subtraction of several values, one of which will effect a zeroizing operation.

Selector return to "0" position

The return of the selector to a zero position is accomplished by mechanism best shown in Figs. 12, 13 and 32. Said mechanism includes a ratchet clutch generally indicated at 223, Fig. 13, which clutch has a ratchet wheel 224 freely rotatable upon a shaft 225. A gear 226 is fixed to the hub portion of the ratchet wheel 224 and meshes with a pinion 227. Said pinion 227 is carried by a shaft 228, which shaft also carries another pinion 229 which meshes with a gear 231 fixed to the shaft 62. Shaft 62 is the power driven shaft which supports the mutilated gears 16 as shown in Fig. 3. It will therefore be seen that the ratchet 224 is continuously driven.

Associated with the ratchet 224 is a ratchet pawl 232, Fig. 32, which pawl is pivotally supported upon a pin 233 mounted between plates 234—234 of the ratchet unit 223. Said pawl 232 is normally urged toward the ratchet wheel by means of a spring 235 but is maintained out of engagement with the ratchet teeth by means

of a cam member 236. Said cam member 236 is pivotally mounted upon a pin 237 and has a projecting finger portion 238 which normally engages a clutch stop 241. Said clutch stop 241 is fixed to a shaft 240 supported in bearings 239, Figs. 1 and 12, which shaft also has an arm 249 fixed thereon. Said arm 249 is connected with the free end of the plunger of solenoid 171 as shown in Fig. 32.

When the clutch stop 241 is withdrawn from the path of the finger 238, upon energization of the solenoid 171, the tension of the spring 235 will urge the pawl 232 into engagement with the ratchet wheel 224, thus effecting a drive of the clutch. Rotation of said clutch will effect the drive of a sleeve 242, Fig. 13, which sleeve is secured to one of the plates 234 and further has an arm 243 fixed thereto. Said arm 243 has a pawl 244 pivotally mounted thereon at 245, Fig. 34, which pawl has a tail portion 246. By means of a spring 247, said pawl 244 is urged toward the peripheral surface of a disc 248 but is normally held out of engagement with said disc due to the tail portion 246 of the pawl 244 being in engagement with a stop 251, which stop projects from a part of the machine frame. When however, the clutch stop 241 is disengaged from the clutch and said clutch is driven through the engagement of the pawl 232 with the ratchet wheel 224, the arm 243 will be rotated with the clutch to therefore move the tail 246 away from the stop 251. Pawl 244 will then be urged into engagement with the peripheral surface of the disc 248 and ride therealong until it engages a lug 252 projecting from the peripheral edge of said disc 248. Upon engagement with said lug the disc 248 will be rotated until the tail 246 of the pawl 244 again engages the stop 251. At this time the clutch stop 241 will have been rocked into the path of finger 238 of the cam member 236 and also into the path of a shoulder 253 on one of the plates 234, to therefore stop the clutch at the end of a full revolution. The means for returning the clutch stop to a stopping position includes an arm 254 which is engaged by a pin 255, Fig. 12, to rock said arm 254 and clutch stop 241 to a clutch stop position.

The disc 248 is fixed to a gear 256, which gear will rotate with said disc 248 in accordance with the drive of said disc by the pawls 244. Gear 256 meshes with an idler gear 257 and said idler gear meshes with a pinion 258 fixed to a shaft 261. Said shaft is supported in bearings 262—262 and also has fixed thereon a pinion 263, Figs. 13 and 4. Meshing with said pinion 263 is a pinion 264, fixed to the shaft 28, which shaft also supports the differentials D and E. Rotation of the gear 256 therefore, will rotate the shaft 28 and such parts which are fixed thereto, which include the selector gear 21, the tens Geneva gear 153, and the sun gear SE of the differential E. Rotation of the selector gear 21 will effect the return of the selector knob 21 and selector dial 117—118 to a zero position through the drive of the selector gear 23 and selector shaft 22. Rotation of the Geneva gear 153 will effect rotation of the Geneva pinion 154, and through said pinion, drive toothed disc 213 and cam members 216 and 217 on the tens side of the compensator unit. Rotation of the sun gear SE, with shaft 23, will, through the gear 81 and pinion 62, effect rotation of the toothed disc 211, which is associated with the units side of the compensator. The clutch stop release, it will be recalled, is ef-

fected at the time the tooth 212 of the units toothed disc 211 or the tooth 215 of the tens toothed disc 213 engage the pawls 191 or 195 respectively to rock the cam members 178-181. This effects the closing of the switch 170 to energize the solenoid 171.

Operation

In the following description it will be shown how the differential system functions and specific values will be provided, first for the setting of a credit, then for the selection and subtraction of certain parts of said credit. In the example chosen, a 25¢ credit will be set up by the insertion of a quarter in the machine. This will provide for operation of the tens and the units side of the mutilated gear credit setting mechanism to thereby set twenty or two steps in the tens credit differential mechanism and five units in the units credit differential mechanism. Next, a selection will be made for a 1½¢ value, which will be printed on two separate letters, to thus leave a balance of 22¢. Then a selection will be made for an 18¢ value, after which the said value will be printed, and since the remaining credit after subtraction will be less than the selected value, the compensating mechanism will operate to effect the return of the selector to a zero position. A credit of 4¢ will still remain, so the final operation will provide for a selection of the 4¢ value and the subtraction of said value during the printing cycle of operation. This will effect the final zeroizing operation of the machine.

It will be stated here, that in each of the operation drawings, about to be described, a motion of the important parts effected in any one operation is indicated by an arrow, the tail of which establishes the starting point of movement and the arrow of which establishes the end or the total distance of movement of the particular part. In this description also, when referring to the parts of the differentials which are operated, reference will only be made to the three principal parts of the differential structure, that is, to the sun gear S, ring gear R and the planetary or spider gears P. In this manner it is believed that the operation will be more clearly understood.

Referring to Fig. 14, the operation for the setting of the two tens values of the quarter in the tens mechanism will be followed. In said Fig. 14, the two-toothed mutilated gear 16t is shown as having driven the pinion 55t the distance of two teeth, which in turn will rotate the gear 61t and shaft 51t to effect the drive of the sun gear SB of the differential B.

Referring to Figs. 4, and 15, the spider PB of the differential B, Fig. 14, is connected with the spider PC of differential C, through gear 85, pinion 86, shaft 17, pinion 90 and gear 91. The gear 91 will also effect the drive of pinions 92, shaft 93 and pinion 94. The drive of the pinion 94 will effect the drive of the gear 95 and the tens numeral wheel 18t. The numeral 2 will thus be set up in the tens wheel so that it will be visible to an operator from the front of the machine.

The pinion 90, through pinion 96 and gear 98 will effect the drive of the ring gear RD of the differential D, a distance indicated by the arrow shown in Fig. 15. From the spider PD, a drive of the tens compensator disc shaft 103 is effected through gears 101 and 102. This will rotate the compensator discs 213, 216 and 217 from the "0" to the 20 position; as shown in Fig. 15. Rotation

of the cam disc 216 will cause the cam 218 to rock the pawl 191 upward, as will be clearly understood from Fig. 35.

The tens credit value of 20 cents is thus entered in both the tens numeral wheel and compensator and in the differentials B, C and D. It will now be shown how the remaining 5 cents of the quarter is set up in each the units numeral wheel and units side of the compensator.

10 Referring to Fig. 16, the five-toothed mutilated gear 16u is shown as having engaged the pinion 55u to rotate the shaft 57u and gear 61u thereon. From said gear 61u, gear 65 and sun gear SA of the differential A will be rotated through five unit positions. Through the gears 78, 66, 68a which are associated with the spider PA, also pinion 68 and gears 68 and 71, a drive is transmitted to the units indicator wheel 18u. Also, from said gear 70, a drive is transmitted to the units compensator disc 211, through the pinion 75 and gears 18 and 79, which effect the drive of the ring gear RE of the differential E, and through the spider PE to gear 81 and pinion 82 associated with the units disc 211.

25 A credit of 25¢ is now set up in a units and tens order in the numeral wheels and in the compensator, also in each of the several differentials. Next, a selection a 1½¢ value will be made.

30 By rotating the selector knob 21, the shaft 22 is rotated, and through the gearing 23, 27, the shaft 23 is rotated. See Figs. 4 and 17. Rotation of said shaft 23 will effect rotation of the sun gear SE of the differential E, and through the spider PE and gears 81 and 82, will effect rotation of the units compensator disc 211 in a counter-clockwise direction, a distance agreeing with 1½ units as indicated in Fig. 17.

35 Also, during the rotation of the shaft 22, the units cam 114, Figs. 7 and 11, is rotated to move the units mutilated gear 110, Fig. 3, to adjust a three-toothed gear portion thereof into alignment with pinion 26u. Also, through the same cam 114, the rocker levers 133 and 146 are adjusted, and through a link connection 151, Fig. 1, between lever 146 and arm 151a, type wheels in the printing drum are adapted to be adjusted to their 1½¢ printing positions. Also, the units Geneva gear 153 will be rotated with relation to the tens Geneva pinion 154, Fig. 4. Also, through the gear 264 on the shaft 28, Figs. 4, 13 and 32, and gear 263 driven thereby, a drive is effected through gears 258, 257 and 256, whereby the lug 252 of disc 248 is adjusted with relation to the zero return pawl 244. The 1½¢ adjustment of the lug 252 is shown in Fig. 31.

40 After the setting of a credit in the machine under control of the coin inserted, and the selection of a value for printing, the machine is ready for the printing of the selected value upon a letter, when it is inserted in the machine.

45 After the tripping of the machine, upon inserting a letter therein, in a manner clearly described in the aforesaid co-pending application, power is applied to the splined shaft 112, Fig. 3, to therefore drive the mutilated gears 110 and effect the rotation of the pinion 26u through three teeth, as indicated in Fig. 18. This will effect rotation of the shaft 155, pinion 156, gear 157 and ring gear RA of the differential A. From the spider PA of said differential A, a drive is effected through gears 76, 66, 68 and 71 to the units numeral wheel 18u. Also from said spider PA, through gears 70, 76, 78, and 79, a drive is effected to the ring gear RE of the differential

E, and from the spider PE of said differential E, a drive is effected through gears 81 and 82 to the units compensator disc 211. Hence, the numeral wheel 18u and the compensator disc 211 are adjusted during the printing cycle to reduce the values therein by $1\frac{1}{2}$ units. As previously stated, the compensator unit is rotated in a counter-clockwise direction both during a selection operation to the value selected and during a subtracting operation, in accordance with the said value selected. Therefore, the compensator units disc 211 will have moved from the 5 position shown in Fig. 16, to the $3\frac{1}{2}$ position shown in Fig. 17, during the selection operation, then to the 2 position of Fig. 18, during the printing cycle of operation. The units numeral wheel 18u however, moves only during the subtraction operation, and thus will register $3\frac{1}{2}$ after $1\frac{1}{2}$ units have been subtracted from the original setting of 5.

After subtracting the $1\frac{1}{2}$ ¢ value, it is again repeated during the printing of the $1\frac{1}{2}$ ¢ value on a second letter. Accordingly, the numeral wheel 18u is reduced to the value 2 and the compensator units disc 211 is adjusted to the value of $\frac{1}{2}$.

The next operation will be to select the value 18¢ for printing. For the selection of said 18¢ value, reference will be made to Fig. 20, wherein the spider PE of the differential E has effected the rotation of the units disc 211 an additional $16\frac{1}{2}$ units to make up the total of 18 units for the desired setting. It will be recalled that the last selection was $1\frac{1}{2}$ ¢, hence an advance of the selector dial an additional $16\frac{1}{2}$ ¢ will result in the 18¢ setting. An advance of $16\frac{1}{2}$ units will effect a full rotation of the disc 211 for ten of the units, plus another $6\frac{1}{2}$ units, or finally resulting in an adjustment of said units compensator disc in a counter-clockwise direction to the 4 position. This is indicated by the position of the tooth 212 opposite the numeral 4, Fig. 20. During the setting to the 18 unit position, the selector shaft 28 and Geneva gear 153 thereon, Fig. 21, will have been rotated a full revolution and one-half a unit upon reaching the "0" position. Upon reaching said "0" position, the Geneva gear 153, will have moved the Geneva pinion 154 to effect movement of the tens disc 213 and cam members 216 and 217 of the tens compensator one tens step in a counter-clockwise direction. Said members 213, 216 and 217 which had been advanced two tens steps in a clockwise direction during the setting of the tens credit have now returned to the 1 position on the tens side. Rotation of the Geneva pinion 154 will also effect rotation of gears 149 and 150 to adjust the differential D as indicated in Fig. 22.

Rotation of the shaft 22 during selection of the 18¢ value, will effect adjustment of the 8¢ mutilated gear of the unit 110 into alignment with the pinion 26u, and further will effect adjustment of the 10¢ mutilated gear of the unit 111 into alignment with the pinion 26t. The type wheels 159 are also adjusted to the value of 18¢ during selection, and the lug 252, on the selector zero return disc 248, is adjusted with relation to the pawl 244 of the mechanism to the position shown in Fig. 32.

When a letter is inserted in the machine to trip same, power will be applied to rotate the splined shaft 112 and therefore rotate the units mutilated gear 110 and the tens mutilated gear 111. The tens mutilated gear will first function to effect the drive of the pinion 26t by the gear agreeing with the tens value and having two

teeth thereon. Referring to Fig. 23, wherein the drive of the pinion 26t by the mutilated gear 111 is shown, the drive of said pinion 26t will effect the drive of the ring gear RC of the differential C through gears 162, 163. From the spider PC, a drive is transmitted through gears 91, 90, 96 and 98 to the ring gear RD of the differential D. From the spider PD of said differential D, the tens compensator shaft 103 is driven, which rotates the tens compensator elements 213, 216 and 217. Said latter compensator elements are thus moved to the "0" position shown as in Fig. 23.

In Fig. 24, the subtraction operation of the 8¢ unit value is shown, the mutilated gear 110 having completed its subtracting operation by rotating the pinion 26u the distance of sixteen teeth. Through the pinion 156 and gear 157, the ring gear RA of the differential A is driven, and through the spider PA and gears 70, 75, 78, 79, a drive is transmitted to the ring gear RE of the differential E. Also, from the spider PE of the differential E, a drive is effected through gears 81 and 82 to the units disc 211 of the compensator.

A further operation which is important to consider with regard to the subtraction of the 8¢ units value is that a transfer will be effected through the Geneva transfer 105—107, which will effect operation of the tens compensator to move the tooth 215 of the disc 213, one step in a negative direction from the "0" position of Fig. 23, to the "9" position, as indicated in Fig. 24. When this occurs, the tooth 215 will engage the tens pawl 195 and rock the tens rocker members 183, 188 in a clockwise direction as viewed in Fig. 24, thereby causing the rise 186 of the cam surface 181, Fig. 35, to engage the roller 171 and rock the arm 176 upward. This will effect the rocking of the shaft 173 and switch arm 172 to close the switch points 110 in the circuit to the solenoid 171. The solenoid 171, as previously stated, will become energized at the completion of a printing cycle to effect the release of the selector return clutch 223 and thereby return the selector to its "0" position. The transfer operation of the Geneva transfer 105—107, has previously been described in detail.

After the subtraction of the second $1\frac{1}{2}$ cent value, the Geneva gear 105 was in the 2¢ position, as will be seen from Fig. 19. Now that the 8¢ units value is to be subtracted, the toothed portion of the Geneva gear 105 will effect the transfer upon passing through the "0" position and will then continue movement to the 4 value position as shown in Fig. 24.

During the latter movement of the Geneva gear 105, the tooth 212 of the units compensator disc 211 passed through eight steps and stopped at the 6 value position or four points negative of the "0" position. No further tripping of the compensator was effected by the tooth 212 however, owing to the pawl 191 being in a raised position, as effected by the rise of the cam surface 218 of the disc 216.

After the selector zeroizing operation, shown in Figs. 33 and 34, the selector dials 117 and 118 will register "0." There is however, a 4¢ credit balance remaining in the differential mechanism and in the credit numeral wheel 18u. The final operation of the machine is to select and print the 4¢ value. The selector is therefore set to the 4¢ value, which operation is indicated in Fig. 29. Here the tooth 212 is shown as having moved from the credit 4 position to the "0" position.

In Fig. 30 the subtracting of the 4¢ selection is

shown, wherein the tooth 212 of the unit compensator disc 211 has effected the tripping of the pawl 191 and rocker members 182, 187 which in turn effect the closing of the switch 170 and the return of the selector to "0." In Fig. 37 the final clearing operation is shown with the compensator returned to its "0" position.

It will be observed from the foregoing that credit entries are made through the sun gears of the differential members of the differentials A and B and that subtractions are made through the ring gears of differentials A and C. The result of either operation, adding or subtracting is registered in the spider. Hence it is possible to insert coins in the machine and add the credit value thereof while letters are being inserted, to effect subtraction of the values printed. In other words both adding and subtracting operations may be effected simultaneously.

Having described the invention, what is claimed is:

1. In a coin controlled machine having a calculating device associated therewith, coin receiving mechanism to receive coins of both a units and tens order, units differential devices settable under control of coins of units denomination received by the coin receiving mechanism to effect registration of units credit values, tens differential devices settable under control of coins of tens denomination received by the coin receiving mechanism to effect registration of tens credit values, manually selective means, means including mutilated gear and pinion members joining the differential devices with the selective means, and means to actuate the mutilated gears and pinions to effect the subtraction of a selected units value from the units differential when the selection is less than ten or a units and tens value from each of the units and tens differentials when the selection is between multiples of ten.

2. In a coin controlled value printing and calculating machine, coin devices having means to receive and move a coin through a predetermined path, driven units mutilated gears having teeth thereon agreeing with each of the units values of coins, driven tens mutilated gears having teeth thereon agreeing with the tens values of coins, units pinions, tens pinions, means connected with the units pinions and adjustable when moved by the coin devices and coins to effect an adjustment of the units pinions into operative relation with the units mutilated gears, means connected with the tens pinions and adjustable when moved by the coin devices and coins to effect an adjustment of the tens pinions into operative relation with the tens mutilated gears, units calculating mechanism operatively connected with the units pinion to register the units values therein, and tens calculating mechanism operatively connected with the tens pinion to register the tens values therein.

3. In a coin controlled calculating machine, a calculating device, coin receiving means, devices operable upon coins received by said coin receiving means, units differential mechanism, tens differential mechanism, means settable under control of coins having units values therein to effect registration of said units values in the units differential mechanism, and means settable under control of coins having tens values therein to effect registration of said tens values in the tens differential mechanism, units subtraction mechanism including connections with the units differential mechanism, tens subtraction mechanism including connections with the tens differential

mechanism, manual selection means connected with the units and tens subtraction mechanism and adapted to set up a value for subtraction within the total credit value, a drive to effect subtraction of the selected value, compensating mechanism connected with each, the credit, subtraction and selection devices and adjustable in accordance with the movement of said devices, and "0" return means connected with the selection devices and compensating mechanism which is operable to return the selection means to "0" when the credit is reduced to a value below a selected value during a subtracting operation.

4. In a coin controlled machine, coin receiving devices therein, calculating mechanism operable under the control of coins received by the coin receiving means for the setting of a credit therein, means to subtract a value from the credit in said calculating mechanism including manually operated value selection means, a mutilated gear having teeth in multiples of two agreeing with a plurality of unit values including a single tooth for a half unit value, a pinion associated with the calculating mechanism, said selection means being adapted to control the relative position between the mutilated gear and pinion, and means to drive the mutilated gear to effect the subtraction of the selected value from the differential means.

5. In a compensator mechanism, a rotative element representing units values, a second rotative element representing tens values, said elements being rotative in a positive direction when establishing a credit of units or tens values, selective means adapted to set a value for subtraction from the credit and connected with each of said rotative elements to rotate one during a units setting operation or the other during a tens setting operation in a negative direction, and means operable by either the units or tens rotative elements, whereby the selective means is returned to "0" when the credit is reduced through subtraction to a value below that for which the selector had been set.

6. In a compensator mechanism, a rotative element representing units values, a second rotative element representing tens values, said elements being rotative from a "0" position in a positive direction when establishing a credit of units or tens values, selective means adapted to select a value for subtraction from the credit and connected with each of said rotative elements to rotate one during a units setting operation or the other during a tens setting operation in a negative direction, subtraction means operable to repeat the rotative movement of the units and/or tens rotative elements in a negative direction in accordance with the value selected for subtraction, and means operable when the units rotative element passes the "0" position in a negative direction, whereby the selective means is automatically re-adjusted to "0" position.

7. In a compensator mechanism, a rotative element representing units values, a second rotative element representing tens values, said elements being rotative in a positive direction when establishing a credit of units or tens values, selective means adapted to set a value for subtraction from the credit and connected with each of said rotative elements to rotate the elements in a negative direction during a value setting operation, said units value element being rotative in a negative direction a distance equal to the units value selected and said tens value element being rotative in a negative direction a

distance equal to the tens value selected, and means operable by either the units or tens rotative elements, whereby, the selective means is returned to "0" when the credit is reduced during subtraction of a selected value to a value below that for which the selector had been set.

8. In a calculating mechanism, a units differential means, a tens differential means; each differential means including a credit receiving element, a value subtracting element, and an element for resolving the difference between the credit and value subtracted; a driven units mutilated gear and a driven tens mutilated gear; a pinion member connected with the subtracting element of the units differential, a pinion member connected with the subtracting element of the tens differential; a manual control including means to adjust the units mutilated gear with relation to the units pinion, and means to adjust the tens mutilated gear with relation to the tens pinion; said mutilated gears being adapted to drive the pinions and associated differentials in accordance with a selected value represented by the number of teeth in the mutilated gears which engage the pinions.

9. In a coin controlled calculating and compensating system, coin receiving means, devices controlled by coins inserted in the coin receiving

means, a differential device, means connecting the coin controlled devices with the differential device to effect the setting of a credit in the differential in accordance with the value of the inserted coins, a second differential device, selection means connected with said second differential device, whereby a value may be set up for subtraction, compensating means operably connected with the second differential device, connections between said first differential device and second differential device, subtracting means associated with the selection means and connected with the first named differential, said compensating means being adapted to be adjusted in a positive direction through the combined operation of both the first and second differentials during credit setting, or be adjusted in a negative direction through operation of the second differential during the selection of a value for subtraction, or further be adjusted in a negative direction through the combined operation of the first and second differentials during a subtraction operation, and means whereby control of the selection means is effected by the compensating means to prevent subtraction of a value greater than the remaining credit.

LINDEN A. THATCHER.
